(57) **CLAIM**

The ornamental design for a reversible closure, as shown and described.

DESCRIPTION

FIG. 1 is a front elevational view of a reversible closure showing our new design in a separated position;

FIG. 2 is a rear elevational view thereof;

FIG. 3 is a top plan view thereof;

FIG. 4 is a bottom plan view thereof;

FIG. 5 is a view in the direction of arrow 5 thereof;

FIG. 6 is a view in the direction of arrow 6 thereof;

FIG. 7 is a view in the direction of arrow 7 thereof;

FIG. 8 is a view in the direction of arrow 8 thereof;

FIG. 9 is a front elevational view of the closure in its closed position;

FIG. 10 is a rear elevational view thereof; and,

FIG. 11 is a cross sectional view taken along the line 11—11 of FIG. 9.
